(57) **CLAIM**

The ornamental design for a garment, as shown and described.

DESCRIPTION

FIG. 1 is a front perspective view of a garment showing my new design;

FIG. 2 is front view of FIG. 1.

FIG. 3 is a back view of FIG. 1.

FIG. 4 is a right side view of FIG. 1.

FIG. 5 is a left side view of FIG. 1.

FIG. 6 is a top view of FIG. 1; and,

FIG. 7 bottom view of FIG. 1.

The broken lines, showing the remaining portions of the garment and portions of the human figure, illustrate the design as worn and form no part of the claimed design.
